UNITED STATES PATENT OFFICE.

GEORGE LITTLE, OF RUTHERFORD PARK, NEW JERSEY.

IMPROVEMENT IN AUTOMATIC TELEGRAPH INSTRUMENTS.

Specification forming part of Letters Patent No. 122,473, dated January 2, 1872.

To all whom it may concern:

Be it known that I, GEORGE LITTLE, of Rutherford Park, in the county of Bergen and State of New Jersey, have invented an Improvement in Automatic Transmitting and Receiving Telegraph Instruments, and the following is declared to be a correct description of the same.

This invention relates to the instrument employed either as a transmitter from a perforated strip of paper or for receiving upon a strip of chemically-prepared paper. My improvement relates to the mechanism for bringing into action either the transmitting or receiving portions of the instrument and the relative arrangement of the parts.

In the drawing Figure 1 is an elevation of the instrument, with the rollers and trough in section to show the paper, the transmitting portions being in position for operation. Fig. 2 is a section detached, showing the transmitting mechanism thrown back ready for the paper to be inserted; and Fig. 3 shows the rollers and transmitting mechanism by a plan view with the receiving mechanism removed.

The frame A receives the electro-magnets b, and the vertical shaft c, and armature of the motor, said motor being provided with the fly-wheel d, governor-balls e, and circuit-breakers f.

This magnetic motor may be constructed substantially the same as in Letters Patent No. 96,332; and I remark that a switch may be employed to make or break the electric circuit from a local battery through said magnets, so as to stop or start the instrument.

The barrel g is upon the shaft 2, that is driven by a worm-gear from the shaft c and this shaft 2, is sustained by the frame h h' that projects from the frame a. A roller, k, is suspended by slings 3 from h and drawn toward the barrel g by a spring, 4, so as to clamp the strip of paper and cause it to progress with the barrel g, and this roller k can be swung back and held by a latch, so as to stop the movement of the paper without stopping the motor. The trough m is sustained by the frame h', and is in metallic contact with the binding-screw 5 of the line or battery-wire, and upon this trough is the insulated stud 6 for the arms n of the transmitting disks i, this stud 6 being connected to the other binding-screw 8 of the line or bat-

tery. This binding-screw 8 is insulated from h'. The rounding projections 9 in the bottom of the trough m act with the disk or disks i to close the circuit through the perforations of the paper as the same is drawn along by the barrel g and roller k. One, two, or more of these disks i may be employed according to the number of rows of perforations in the strip of paper, and the insulated springs 10 serve to press the disks down with the necessary force. When the transmitting portion of the instrument is not in use the disk or disks i and arms may be held up by a pin, 12, inserted into a hole in the side of the trough m, the same being insulated, so as not to close the electric circuit. The detaining-brush s serves to produce a friction upon the paper sufficient to keep it to the surface of the barrel g, and this brush s is made to turn upon a stud, 14, and is kept down by a spring, 15. The catch-finger t taking against the arms n lifts them and the disks i, and falling into a notch on the arm n the parts are held back while the paper is being introduced, as seen in Fig. 2. As the brush is turned down this catch-finger is liberated from n and pressed upon the paper by the spring 15. The transmitting-rollers or disks v, such as in my patent No. 96,333, are at the end of springs u, that project from the arm v' in the swinging head w, and this head is hinged at 16 to the insulated block x, that is in metallic contact with 8, by the bar 17, and the spring-fork 18 serves to hold the head w when either turned back, as in Fig. 1, or when turned down, as shown by dotted lines in the same figure. The small screws 19 prevent the springs u being bent by the blow of the rollers v in striking the barrel g as the head is thrown over.

By this construction the machine is capable of use in either transmitting or receiving, and can be instantly changed to either one use or the other.

Either single or double disks or receiving-points may be employed, as desired. The spring 20, from h to the shaft 2 of g, insures metallic contact with the barrel g, for the purposes of receiving upon chemically-prepared paper.

I claim as my invention—

1. The swinging-brush s and catch-finger t, combined with the arm of the transmitting de-

vice, substantially as set forth, and for the purposes specified.

2. The arrangement of the transmitting and receiving devices and the electric connections, substantially as specified, so as to employ the barrel *g* and trough *m* for the paper in either transmitting or receiving, as set forth.

3. Two transmitting rollers or disks *v*, arranged upon separate spring arms, so as to act

in connection with a strip of paper having perforations in two lines, substantially as set forth.

Signed by me this 6th day of November, A. D. 1871.

GEO. LITTLE.
